OF NEW YORK.

PILE FABRIC.

Application filed August 30, 1927. Serial No. 216,382.

The present invention relates to pile fabrics and an object thereof is to effectively secure to a pile fabric such as an Axminster rug a fringe.

5 To this and other ends, the invention consists of certain parts and combinations of parts all of which will be hereinafter described; the novel features being pointed out in the appended claim.

10 In the drawings:

Fig. 1 is a fragment of a pile fabric showing the fringe attached;

Fig. 2 is a vertical section through the fabric and the fringe.

15 The securing of fringe to pile fabrics such as Axminster rugs has not been done heretofore because of the tendency of pile fabric to fray or unravel, and, if to prevent this, the fabric is turned or overlapped at the fringe 20 edge, then the material becomes too thick at this point.

With this invention it is possible to secure a fringe to a pile fabric without danger 25 of unraveling and at the same time the fabric is not thickened at the point where the fringe is secured.

In the illustrated embodiment of the in-

vention, 1 indicates the pile fabric which has one or more edges provided with a break in the pile extending longitudinally of said edge. 30 This break is folded or turned longitudinally at 2 to provide a lower portion 3 and an upper or overlapping portion 4, the free edge of which extends preferably to the pile and abuts the latter. The braid 5 of the fringe 6 35 is superimposed on the overlapping portion 4 and stitching is passed through the braid and the two portions of the break to secure the fringe.

With this invention a fringe may be secured to the edge of a pile fabric without any danger of unraveling and without also increasing the thickness of the pile fabric at the seam between the fringe and the pile fabric.

What we claim as our invention and desire 45 to secure by Letters Patent is:

The combination with a pile fabric having a break in the pile along an edge, the break being turned to provide an overlapping portion on the upper side of the fabric beyond the pile surface, and a fringe secured on the upper face of said overlapping portion.

JOSEPH A. COYLE.
